SELF-WRINKING MOP

Virgil Kenneth Cooper, Hollywood, Calif.

Application March 8, 1949, Serial No. 80,144

5 Claims. (Cl. 15—120)

1

My invention relates generally to mops and more particularly to wet mops in the self-wringing class.

Mops may be divided into two general types, dry mops for removing dust or loose dirt which are often treated with chemicals to aid in dusting, and wet mops which are immersed in cleaning liquid and used to apply the latter to a floor or other surface to be cleaned. Some mops of this second type are provided with wringing mechanisms to remove liquid from the cloth without the necessity of handling the cloth, and these are known as self-wringing mops.

The device I provide is an improved mop of this latter class having an efficient wringing means combined with a cloth guiding means and other advantageous features in a mop which may be easily manufactured and sold at a relatively low price.

One of the major advantages of using a self-wringing mop is that the user does not get dirty or wet when wringing the mop. Heretofore this advantage has been achieved by providing a wringing mechanism that is time-consuming in operation, and that does not wring the mop as well as does hand wringing. In addition, many such mops are bulky, awkward to handle, and cannot be moved easily into obstructed spaces. I have overcome these disadvantages in my improved mop whose wringing efficiency is equal or greater than that achieved by hand wringing. The guided cloth may be moved easily under projecting ledges, against baseboards, or into obstructed spaces, and is so designed as to present a large absorbent surface area without becoming bulky.

It is, therefore, an object of my invention to provide a mop wherein the wringing mechanism effects the liquid removal by a twisting and squeezing motion that is essentially the same as is used in hand wringing. The user has a mechanical advantage in operating the wringing mechanism, whereby the mop can be wrung drier than a conventional mop with the expenditure of considerably less energy.

Another object of my invention is to provide a wringing mechanism which is always ready for use and which is operated by one simple motion.

A further object of my invention is to provide a mop cloth which has an inner stiffening means that holds the cloth in shape, and guides its movement as directed.

Still another object of my invention is to provide a mop whose handle may be left standing substantially erect without external support.

2

It is also an object of my invention to provide a sturdy, self-wringing mop having a minimum of parts all of which are lightweight and easily formed.

5 These and other objects and novel features of my invention will become apparent from the following detailed description and from an inspection of the accompanying drawings in which,

Fig. 1 is a perspective view of my improved mop shown positioned for use,

Fig. 2 is a perspective view of the mop head showing the operating arm partially rotated to wring a mop cloth,

Fig. 3 is a top plan view of the device with the holder and attached cloth shown in detail,

Fig. 4 is a vertical cross section taken along the line 4—4 of Fig. 3 showing the stiffening rod pivoted forwardly within the guide slot,

Fig. 5 is a side elevation with the stiffening rod shown in the vertical position permitting rotation of the operating arm,

Fig. 6 is a cross section taken along the line 6—6 of Fig. 5 showing the shape of the upper cloth holder,

25 Fig. 7 is a perspective view showing a cloth partially fitted onto the cloth holder, and

Fig. 8 is a vertical cross section with the stiffening rod shown pivoted rearwardly so that the mop handle will stand without external support.

Referring now to the drawings and particularly to Fig. 1 thereof, the numeral 10 indicates an elongated handle usually made of wood. Firmly held on the forward end of the handle 10 is a head 11 carrying a mop cloth holder 12 to support thereon a mop cloth 13. The cloth normally hangs downwardly and is engaged at its lower end with a spreader 14 as best seen in Fig. 7. Supporting the spreader 14 is a stiffening rod 15 which extends through the cloth 13 and is connected at its upper end to a rotatable operating arm 16 through a shaft 17 so that the operating arm and spreader rotate together. The lower edge of the cloth 13 may thus be twisted with respect to its upper edge in a wringing action that removes liquid from the cloth.

40 The head 11 is a generally box-like structure which may be easily shaped from a single flat sheet of metal for economical and lightweight construction. A flat and generally horizontal upper wall 21 is held forwardly of the handle 10 by a rear portion having rounded sides which converge inwardly to fit around the handle in the shape of an upper half 20a of a longitudinally split ferrule 20.

45 A central aperture in the wall 21 journals an

operating shaft 17 to be described later, and directs the shaft downwardly into the head 11 substantially perpendicular to the surface of the wall. The front of the upper wall 21 is bent downwardly to form a forward wall 22 which is inclined outwardly away from the handle 10 and is somewhat longer than the shaft 17 so that a bottom wall 23 which continues rearwardly from the forward wall passes beneath the end of the shaft. Laterally extending side portions or ears 24 are formed on the bottom wall 23 to affix the holder 12 to the head 11, and the bottom wall diverges rearwardly from the upper wall 21 causing the holder to lie substantially horizontal when the mop handle 10 is inclined upwardly at 15 the normal angle for mopping. The sides of the box-like head 11 are open and the structure is completed by a short rear wall 25 and a lower longitudinal half 20b of the ferrule 20 which fits around the handle 10, and with the upper 20 half 20a forms a complete cylindrical sleeve. The ferrule 20 is held together by suitable means such as the pins 26 and the head 11 is firmly attached to the handle 10. Other types of holding means may be used but I prefer the ferrule 25 20 since it prevents end splitting of the handle 10 and is easily formed, while it is of course possible to modify the head 11 or to form it in another manner, I prefer the particular structure shown since it is sturdy and lightweight.

The cloth holder 12 is preferably a formed rod or bar having a U-shaped central section 30 whose mouth faces forwardly and has opposed rectangular loops 31 extending laterally therefrom. The front portions of the loops 31 extend 35 outwardly substantially perpendicular to the side of the U-shaped center section 30 and the lateral ends of the loops are curved rearwardly to form semi-circular portions substantially the width of the center section. The rear portions 40 of the loops 31 extend inwardly parallel to and rearwardly spaced from the front portions and terminate near but do not quite meet the base of the U-shaped center section 30. In effect, the holder 12 forms an oval loop having a gap on 45 its rear side, with the terminal ends of the loops opposing each other at the edges of the gap, thus allowing the loop ends to be introduced into a sleeve-like hem 32 of the mop cloth 13. As previously mentioned, a pair of ears 24 are 50 formed on the sides of the bottom wall 23, and the holder 12 is attached to the head 11 by bending the ears upwardly and inwardly around the side members of the section 30 to form cylindrical enclosing sleeves. The holder 12 is held 55 perpendicular to the handle 10 and the loops 31 extend laterally outwardly to form with the handle a T-shaped structure.

The spreader 14 is similarly formed from a single rod or bar having a slightly indented or 60 U-shaped central portion 33 facing forwardly with opposed rectangular loops 34 extending laterally therefrom. As in the cloth holder 12, the lateral portions of the loops 34 are curved and the end portions are rearwardly spaced from the front portions to terminate near but not quite meet the central section 33. The spreader 14 is normally held parallel to and downwardly spaced from the holder 12 by the stiffening rod 15 which is welded or otherwise firmly attached to the 65 central portion 33 of the spreader, and extends upwardly to connect with the operating shaft 17. The spreader 14 may, if desired, be formed integrally with the rod 15 to simplify construction.

The cloth 13 is rectangular in shape to fit between the holder 12 and the spreader 14 and may be of any suitable material for absorbing liquid such as string, rope, or loose weave cloth. The preferred form shown herein is of the string type but any of the other types can be used equally well. The strands are formed as continuous loops in side-by-side relationship joined together and bound at the upper edge by the open ended sleeve-like hem 32 and at the lower edge by a similar sleeve or hem 35. These sleeves are made of heavy doubled canvas or other suitable material to pad the holder 12 and spreader 14 and firmly hold the strands in place.

To attach the cloth 13 on the holder 12, one end of the sleeve 32 is fitted over the rear terminal end of one loop 31 and about one half of the length of the sleeve is pushed on this loop until the sleeve end is at the mouth of the U-shaped section 30 on the forward side of the holder. The other end of the sleeve 32 is then started on the rear terminal end of the opposing loop 31 and pushed around to the U-shaped section on the forward side of the holder. The central portion of the sleeve 32 thus passes rearwardly of the base of the U-shaped section 30, and the cloth 13 forms a complete bag or envelope open only slightly at the front. A partially installed cloth 13 is shown in Fig. 7 and as can be seen, the ends of the sleeve 35 are similarly fitted on the rear opposing terminal ends of the loops 34 forming the spreader 14, and the sleeve ends are pushed around the loops to meet at the front.

The cloth 13 forms a bag-light envelope enclosing the stiffening rod 15 and the sleeves 32 and 35 pad the holder 12 and spreader 14 so that none of the frame members can scratch or otherwise mar the floor. The holder 12 and spreader 14 hold the cloth 13 firmly thereon and it cannot come off even when considerable force is applied in wringing. Furthermore, the cloth always maintains its flat surface shape, whether pushed or pulled and thus is very useful in working against baseboards and under low projecting ledges. The first cost of the cloth 13 is low because of its simple construction, and it has a long life which keeps the maintenance costs low. This is possible since all of the surface of the cloth 13 is available for use, and as desired, the cloth may be turned inside-out when placed on the loop members to evenly distribute the wear on the strands.

As will be remembered, the operating shaft 17 is journaled in the upper wall 21 and extends downwardly into the box-like head 11 in a substantially vertical direction. A horizontal opening is bored in the lower end of the shaft 17 and an upper section 41 of an L-shaped hook end 40 on the stiffening rod 15 is pivotally held therein, the rod 15 being rotatable with the shaft 17 or free to pivot separately in a vertical plane about the hook section 41. Formed in the forward wall 22 of the head 11 is a vertical guide slot 42 which extends through the bottom wall 23 and up a short distance on the rear wall 25 to determine a vertical plane extending along the longitudinal axis of the mop. The rod 15 may rotate or pivot within this slot 42 which is of sufficient width to permit free movement therein, but necessarily restricts lateral movement of the rod. The ends of the slot 42 determine the forward and rearward limits of the arc in which the rod 15 may pivot and the rear limit of the arc is also determined by the base of the U-shaped sec-

tion 30 which lies transversely across the slot 42. When the rod 15 bears against the base of the U-shaped section 30 the handle 10 is able to stand without external support as will be described hereinafter.

At the upper end of the shaft 17 above the wall 21 is another horizontally bored opening which carries one end of the operating arm 16, the opposite end of the arm being upturned and supporting a rotatable hand knob 43. When the arm 16 is in its normal position it points along the longitudinal axis of the mop towards the handle 10 and in this position, the lower opening carrying the hook section 41 is transversely directed across the head 11 and is perpendicular to the arm 16 so that the rod 15 is free to pivot in the plane determined by the guide slot 42.

This position of the arm 16 is best seen in Fig. 4 wherein the rod 15 has pivoted forwardly about the hook section 41. It is to be noted that once the rod 15 has pivoted forwardly or rearwardly the operating arm 16 cannot be rotated since the angled connection between the shaft 17 and the rod would cause the rod to swing laterally as the shaft rotates, and the guide slot 42 restricts lateral movement of the rod. When the mop is raised from the floor, the weight of the spreader 14 and the cloth 13 causes the rod 15 to fall to the vertical position and the arm 16 is then free to rotate as shown in Fig. 5.

The shaft 17 is held from axial movement by collar means above and below the wall 21 and in the preferred form I show an economical and satisfactory way of doing this, although of course other types of collar or shoulder means may be used. On the shaft 17 below the wall 21 are two collars or washers 44 spaced apart by a thicker resilient washer 45, the lower collar seating against a small shoulder 46 on the shaft. In assembling the mechanism the shaft 17 is pushed up through the aperture in the wall 21 until the upper collar 44 bears against the wall 21. A similar collar 47 is then fitted over the upper end of the shaft 17 and held in place against the wall 21 by the arm 16 which is inserted through the upper horizontal opening in the shaft. In order to push the end of the arm 16 through the shaft 17 it is necessary to somewhat compress the resilient washer 45, hence after being assembled the arm 16 is held tightly against the upper washer 47 and the shaft is restricted from axial movement or from rotation due to vibration or jarring.

Rotation of the arm 16 rotates the rod 15 and the attached spreader 14 to twist the mop cloth 13 between the spreader and holder 12. The wringing action which occurs is basically the same as the conventional action of holding the mop head in one hand and twisting the cloth with the other hand. The user holds the handle 10 with one hand and rotates the arm 16 with the other. This single motion is made easy even for a person of slight strength because the leverage of the arm 16 gives the user a mechanical advantage. The amount of rotation of the arm 16 necessary to effect the wringing will of course depend upon the particular modifications of the device, but in the utility or household type herein shown, about 1½ revolutions of the arm will cause the cloth 13 to be tightly twisted and any liquid contained in the cloth will be wrung out. The wringing mechanism both twists and squeezes the strings of the cloth 13 and is highly efficient, much more so than a mechanism such as a roller type wringing mechanism which only

squeezes the cloth. All of the liquid wrung from the mop cloth is directed downwardly and there is no necessity for the user to get dirty or wet.

When the mop is wrung dry the arm 16 is 5 reversely rotated to its normal position and the stiffening rod 15 is free to pivot forwardly or rearwardly in the guide slot 42. The rod 15 is normally pivoted forwardly as best seen in Fig. 4 and the rear surface of the cloth 13 is used to mop the 10 floor. As previously mentioned, the mop can be pushed or pulled without affecting the shape of the cloth 13, and because of the guiding mechanism it may be easily moved into corners or the like. There is no restriction on the mopping angle and the handle 10 can be lowered level with the floor if it is desired to push the mop under a low overhang.

Since the cloth 13 and rod 15 hang vertically when the mop is elevated from the floor, it is easy to pivot the rod rearwardly and utilize the front side of the cloth 13 for mopping. This greatly increases the liquid absorbing capacity of the cloth 13 and permits less frequent wringing. In this position, shown only in Fig. 8, the 25 handle 10 may be left standing substantially erect without external support. As the rod 15 pivots rearwardly it is limited in its travel by the base of the U-shaped section 30 which extends across the guide slot 42. The rod 15 bears upwardly 30 against the base of the U-shaped section 30 and the handle 10 is held in an upwardly inclined position. The laterally extending holder 12 and spreader 14 which are enclosed within the cloth 13 form a substantially rectangular base upon 35 which the mop stands firmly. This feature is very desirable when an interruption forces the user to leave the mop temporarily and avoids the frequent mishaps caused by leaving the mop standing within the mop bucket or inclined 40 against a vertical surface.

It is to be noted that the latter feature has been provided without additional mechanism and it can be seen that throughout the mop there is a simplicity of construction. All of the parts are 45 lightweight and easily formed and yet the complete mop is sturdy and durable. It is also apparent that various modifications can be made in the design and construction by those skilled in the art which will in no way depart from the 50 spirit of my invention, and I do not wish to be limited to the particular form herein shown and described except as defined in the appended claims.

I claim:

1. A self-wringing mop which includes: a handle; a head member attached rigidly to the forward end of said handle, said member having an aperture therethrough transverse of said handle and a vertical guide slot therein; a rigid holder extending laterally from said member and adapted to carry the upper edge of a mop cloth; a shaft rotatably mounted in said aperture; a stiffening rod extending outwardly through said guide slot and pivotally connected at its upper end to said shaft for free movement along the plane of said slot through operating position angled forwardly and rearwardly of said handle to a wringing position in substantial alignment with said shaft, the pivotal connection being on an axis perpendicular to said shaft axis, whereby said stiffening rod is rotatable with said shaft in the wringing position and is held against rotation in the operating positions by the edges of said guide slot; a lateral spreader connected to the free end of said rod and adapted to engage

with the lower edge of said cloth; and an operating arm connected to said shaft above said head member to rotate said spreader when said rod is in the wringing position.

2. A self-wringing mop which includes: a handle; a head member attached rigidly to the forward end of said handle; a lateral holder extending rigidly from said member for engagement with the upper edge of a mop cloth; a shaft means mounted in said member for rotation about an axis transverse of said handle; vertical guide means in said head member extending longitudinally of said handle; a stiffening rod extending outwardly through said guide means and pivotally connected at its upper end to said shaft; means for free movement along the plane of said guide means through operating positions angled forwardly and rearwardly of said handle to a wringing position in substantial alignment with said shaft, the pivotal connection being on an axis perpendicular to said shaft axis, whereby said stiffening rod is rotatable with said shaft in the wringing position and is held against rotation in the operating positions by the edges of said guide means; a lateral spreader connected to the free end of said rod and adapted to engage with the lower edge of said cloth; and operating means for rotation of said shaft.

3. A self-wringing mop which includes: a handle; a head member rigidly attached to an end of said handle and having a vertical guide slot extending longitudinally therein; a lateral holder extending rigidly from the sides of said head member and adapted to carry the upper edge of a mop cloth; a stiffening rod extending downwardly through said vertical guide slot and freely pivotal therein; a lateral spreader centrally connected to said stiffening rod and adapted to engage with the lower edge of said cloth; a rotatable shaft journaled in said head member on an axis transverse of said handle and in the plane of said slot; and pivotally connected to said stiffening rod on an axis perpendicular to the axis of said shaft whereby said rod can rotate with said shaft and pivot about its connection to said shaft within said guide slot; and an operating arm extending from the upper portion of said shaft to rotate it and said lateral spreader to thereby wring said cloth.

4. A self-wringing mop which includes: a handle; a head member attached to one end of said handle by a rearwardly extending ferrule, said head member having a substantially longitudinal upper wall with an aperture transverse of said handle therein, and a vertical guide slot extending longitudinally of said handle; a cloth holder having a U-shaped central section attached to said head member with the mouth of the U-section facing forwardly and a pair of loops extending laterally therefrom returning rearwardly to terminal ends spaced apart near the base of said U-shaped section, said loops being adapted to carry the upper edge of a mop cloth thereon; a spreader having a pair of laterally extending loops adapted to engage the lower edge of said mop cloth, said loops being connected in the front by a continuous central section, and returning rearwardly with the terminal ends thereof of spaced apart; a stiffening rod connected to the central section of said spreader and extend-

ing upwardly to pass through said guide slot; a pivotal hook on the upper end of said rod; a rotatable shaft journaled in said upper wall aperture having a pivotal connection perpendicular to the axis of said shaft in its lower end to receive the hook end of said rod and pivotally support the same for movement within said guide slot and rotation with said shaft; and an arm mounted on the upper end of said shaft to rotate it and said spreader and thereby wring said cloth.

5. A self-wringing mop which includes: a handle; a head member attached to one end of said handle by a rearwardly extending ferrule, said head member having a substantially longitudinal upper wall with an aperture transverse to said handle therein, and a vertical guide slot extending longitudinally of said handle ears projecting from the sides of said head member; a cloth holder having a U-shaped central section attached to said holder by said ears, with the mouth of the U-section facing forwardly, and a pair of loops extending laterally therefrom which return and have rear terminal ends spaced apart and near the base of said U-shaped section; a cloth on said holder that normally hangs downwardly from an open-ended upper sleeve which surrounds said holder loops with its ends at the mouth of said U-shaped central section and the center portion of said sleeve bridging the space between said rear terminal ends; a similar open-ended sleeve at the lower edge of said cloth; a spreader having a pair of laterally extending loops engaged with said lower sleeve, said loops being connected in the front by a continuous central section and returning rearwardly with the terminal ends thereof spaced apart; a stiffening rod centrally connected to said spreader and extending upwardly to pass through said guide slot in said head member; a pivotal hook on the upper end of said rod; a rotatable shaft journaled in the aperture of said upper wall having a pivotal connection perpendicular to the axis of said shaft in its lower end to receive the hook end of said rod and pivotally support the same for movement within said guide slot and rotation with said shaft; and an arm mounted on the upper end of said shaft to rotate it and said spreader and thereby wring said cloth.
